Inventor:

R. M. Hunter.

UNITED STATES PATENT OFFICE.

RUDOLPH M. HUNTER, OF PHILADELPHIA, PENNSYLVANIA, ASSIGNOR TO
THE ELECTRIC CAR COMPANY OF AMERICA, OF SAME PLACE.

ELECTRIC RAILWAY.

SPECIFICATION forming part of Letters Patent No. 448,618, dated March 17, 1891.

Original application filed September 23, 1886, Serial No. 214,309. Divided and this application filed September 1, 1890. Serial No. 363,636. (No model.)

To all whom it may concern:

Be it known that I, RUDOLPH M. HUNTER, of the city and county of Philadelphia, and State of Pennsylvania, have invented an Improvement in Electric Railways, of which the following is a specification.

My invention has reference to electric railways; and it consists of certain improvements which are fully set forth in the following specification, and shown in the accompanying drawings, which form a part thereof.

This application (Case 162) is a division of my application, Serial No. 214,309, filed September 23, 1886.

15 The object of my invention is to provide a construction, for an electric railway wherein a conductor shall be suspended above the railway and adapted to supply current to the electrically-propelled vehicle supported upon 20 the track-rails of the railway, said rails forming the return-circuit of the system, and in which the car is provided with an underrunning contact making a traveling connection with the under and exposed surface of the 25 suspended conductor.

Furthermore, my invention comprehends the employment, in an electric railway in which there are two or more tracks, of a separate suspended conductor for each track for 30 supplying electric current to the cars moving upon the said tracks and the employment of the track-rails of the respective tracks as return-conductors. In this construction the various conductors for supplying current to 35 the electrically-propelled vehicles are coupled in parallel and with one pole of the generating apparatus, while the track-rails are also coupled in parallel and connected with the other pole of the electric generator. The cars, 40 as before stated, are provided with a contact device for making connection with the suspended conductors, and, preferably, said contact device is an upwardly-extending underrunning contact. By this construction I am 45 enabled to lighten the overhead structure by providing a single working-conductor and employing the track-rails and earth as the return. Furthermore, the said suspended conductor, arranged above the railway, may 50 be light and flexible, as the contact device is

preferably supported by the vehicle, and the weight thereof is not borne by the conductor. The car is provided with an electric motor mechanically connected with the axle for rotating it, and the current is supplied to the 55 motor from the overhead collector through a suitable regulator or resistance-changer. The current after leaving the motor is delivered by the wheels or otherwise to the rails. If desired, the suspended working-conductor 60 may be supported above and parallel to the railway by suitable supporting-posts and laterally-projecting arms or extensions, and current may be supplied thereto from an auxiliary or supply cable or conductor extending 65 along the railway in any suitable manner, but preferably supported upon the same posts or poles and electrically connected at intervals with the working-conductor.

In the drawings, Figures 1, 2, and 3 are plan 70 views or diagrams showing several arrangements of railways embodying my improvements. Figs. 4 and 5 are cross-sections through railways, showing two forms of suspended conductors for supplying current to the electrical 75 vehicle and illustrating an upwardly-extending under running contact carried by the vehicle; and Fig. 6 is a similar view, but one in which the suspended conductor is located 80 within a conduit.

Referring first to Fig. 1, B represents the track-rails of the main line, and B' the suspended electrical conductor for supplying current to the motor. The conductor B' is preferably the positive conductor, and the rails B 85 act as a return-conductor. A' is the generator for supplying electric current to the conductors B and B'. I represent track-rails of a parallel railway or turn-out and are electrically connected with the track-rails B of the 90 main line. I' is the suspended conductor of the turn-out rails I, and is electrically connected with the conductor B' of the main line.

Referring to Fig. 2 I have the track-rail conductors B and suspended conductor B' 95 bent into a loop B⁷ and formed into a return-railway I⁴, which may be connected with the main track at a point nearer the generator A'.

Referring to Fig. 3 I have three parallel railway-tracks, two of which are shown by 100

dotted lines as connected by a loop at one end, so that a car may pass up one track and down the other. The third railway-track (marked 1⁵) is shown as connected by a switch with one of the other tracks. The rails of these several tracks are marked B, and each of them is provided with a suspended conductor B', all of which suspended conductors are coupled in parallel with one pole of the generator A', and all of the conductor-rails B are coupled in parallel with the other pole of the generator A'.

In Figs. 1, 2, and 3 of this application I have shown heavy parallel lines to indicate the rails and a light line interposed between them to indicate the suspended conductor. In the corresponding figures of the original application the positive and negative circuits alone were indicated, and were adapted to either of the various specific constructions shown in the other figures of the said application. When the circuits of Figs. 11, 12, and 13 of the original application are applied to the system shown in Fig. 26 of said application, I have the construction set out in this application. These Figs. 1, 2, and 3 differ from those of the original application only in duplicating the negative conductors, which is the natural result of using the rails as the return-conductor.

In Fig. 4, A is a pole arranged along the side of the railway-track, and is provided at the upper part with a laterally-projecting arm A⁵, made V shape, which arm normally supports the suspended conductor B'. The car is provided with an upwardly-extending collector-arm C', carrying upon its upper end a grooved contact-wheel C², which makes an underrunning contact with the suspended conductor B', which is arranged at a distance above the railway-track. D² is an electric motor mechanically connected with the axle of the car for rotating it, and current is supplied from the collector to the motor by a circuit E on the car provided with a current-regulator or resistance-changer E'. There are a series of posts A arranged on the side of the railway, so that the conductor B' is suspended at intervals and held at an elevation preferably out of reach of persons passing along the railway. As the collector moves along in contact with the under portion of the conductor, the latter is raised as the collector passes over the laterally-projecting arms A⁵. If desired, current may be supplied to the working-conductor B' from a supply-conductor b, supported upon the posts A out of reach of the collector and electrically connected at intervals with the conductor B' by means of the metal brackets A⁵ or otherwise.

In Fig. 5 I have substantially the same general construction; but in this case the suspended working-conductor B' is supported from the posts A by laterally-projecting arms B³, permanently connected with the upper edge of the conductor. The upwardly-extending contact-arm C' carries, as before, a grooved

contact-wheel C², making an underrunning contact with the conductor B', and yet is out of reach of the supply-conductor b, which, as in case of Fig. 4, is connected electrically at intervals with the working-conductor B'. The supply-conductor b is shown in dotted lines in Fig. 1.

In the case of the construction shown in Fig. 6 I have the working-conductor B' suspended within a slotted conduit K, and the collector-arm C' is supported upon the axles of the car, with provision for lateral movement by being supported in suitable transverse guides, and the arm carries the underrunning contact-wheel C², as before. In all these cases the rails act as the return-conductor, and the current is supplied to an underrunning contact-collector, supported wholly by the car, from a suspended conductor whose under surface is unobstructed and exposed. The supply-conductor b may or may not be used, as desired, but is desirable where the railway is very long or where a large number of cars are operating upon a shorter railway. It is evident that the current-collecting devices for all positions of the suspended conductor B may be made laterally movable, if so desired.

I do not limit myself to the mere details of construction, as they may be modified in various ways without departing from the principles of my invention.

Having now described my invention, what I claim as new, and desire to secure by Letters Patent, is—

1. In an electric railway, the combination of a looped track forming a return-circuit and connecting with one pole of the generator, a looped conductor extending along the railway electrically independent of the rails of the track and having its opposite ends connected with the other pole of the generator, an electrically-propelled vehicle having a motor mechanically connected to rotate the axle, a current-collecting device supported by the vehicle and making a traveling connection with the conductor, and a motor-circuit carried upon the vehicle, including the motor and connecting the collector device with the rails.

2. In an electric railway, the combination of a track forming a return-circuit and connecting with one pole of the generator, a conductor extending along the railway electrically independent of the rails of the track and connected with the other pole of the generator, an electrically-propelled vehicle having a motor mechanically connected to rotate the axle, a laterally-movable current-collecting device supported wholly by the vehicle and making a traveling connection with the conductor, a motor-circuit carried upon the vehicle, including the motor and connecting the collector device with the rails, and a current-regulator upon the vehicle for controlling the current passing through the motor-circuit and motor.

3. In an electric railway, the combination

of the track-rails forming the return-circuit and electrically connected with one pole of the generator, a suspended conductor arranged at a considerable elevation above the 5 track-rails and receiving current from the other pole of the generator, an electrically-propelled vehicle having a roof and provided with an electric motor mechanically connected to rotate its axle, a current-regulator

10 for controlling the current delivered to the motor, and a long upwardly-extending current-collecting device having a grooved roller carried by the vehicle above its roof out of reach of passengers and making a continuous 15 contact with the suspended conductor, and an electric circuit between the current-collecting device and rails, including the electric motor and current-regulator.

4. In an electric railway, the combination 20 of the track-rails forming the return-circuit and electrically connected with one pole of the generator, a suspended conductor extending along the railway at a different elevation from the rails and electrically independent 25 thereof and electrically connected with the other pole of the generator, an electrically-propelled vehicle having an electric motor mechanically connected to rotate the axle, a laterally-movable current-collecting device 30 carried by the vehicle and making an underrunning contact with the conductor, and a circuit extending from the current-collecting device to the rails, including the electric motor.

35 5. The combination of two or more railway-tracks the rails of which are electrically connected together and with one pole of the generator, a separate conductor for each railway-track arranged at a different elevation than 40 the railway-tracks and electrically independent of the rails and also electrically connected together and with the other pole of the generator, an electrically-propelled vehicle having an electric motor mechanically connected 45 to rotate the axle, a current-collecting device making a continuous contact with the conductor, which is independent of the rails and a circuit carried by the car, including the electric motor and connecting the current-collecting device with the rails.

60 6. The combination of two or more railway-tracks the rails of which are electrically connected together and with one pole of the generator, a separate suspended conductor for 55 each railway-track electrically independent of the rails and also electrically connected together and with the other pole of the generator, an electrically-propelled vehicle having an electric motor mechanically connected to 60 rotate the axle, a current-collecting device making a continuous contact with the suspended conductor, carried by the vehicle and provided with an underrunning contact part moving in connection with the under surface of the 65 suspended conductor, which is independent of the rails, a circuit carried by the car, including the electric motor and connecting the current-collecting device with the rails, and a supply-conductor extending along the railway out of reach of the suspended conductor and electrically connected at intervals with the conductor or conductors with which the contact device makes connection.

65 10. In an electric railway, the combination 130 of two or more tracks the rails of which form return-conductors and are electrically connected together and with one pole of the generator, with a separate suspended conductor

necting the current-collecting device with the rails.

7. In an electric railway, the combination 70 of two or more tracks the rails of which form return-conductors and are electrically connected together and with one pole of a generator, with a separate suspended conductor arranged at an elevation above each of the 75 tracks and also electrically connected together and with the other pole of the generator, one or more electrically-propelled vehicles for said railway-tracks, provided with an electric motor mechanically arranged to 80 rotate the axle, an upwardly-extending current-collecting device making a running contact with the suspended conductor, and an electric circuit on the vehicle, including the motor and connecting the current-collecting 85 device with the rails.

8. In an electric railway, the combination 90 of two or more tracks the rails of which form return-conductors and are electrically connected together and with one pole of a generator, a separate suspended conductor arranged at an elevation above each of the tracks and also electrically connected together and with the other pole of the generator, one or more electrically-propelled vehicles for 95 said railway-tracks, provided with an electric motor mechanically arranged to rotate the axle, a current-collecting device consisting of an upwardly-extending arm arranged above the roof of the vehicle and provided with a 100 grooved contact portion (in the groove of which the conductor rests) for making an underrunning contact with the suspended conductor, and an electric circuit on the vehicle, including the motor and connecting the current-collecting device with the rails.

9. The combination of two or more railway-tracks the rails of which are electrically connected together and with one pole of the generator, a separate suspended conductor for 110 each railway-track and electrically independent of the rails and also electrically connected together and with the other pole of the generator, an electrically-propelled vehicle having an electric motor mechanically connected 115 to rotate the axle, a current-collecting device making a continuous contact with the conductor, carried by the vehicle and provided with an underrunning contact part moving in connection with the under surface of the 120 suspended conductor, which is independent of the rails, a circuit carried by the car, including the electric motor and connecting the current-collecting device with the rails, and a supply-conductor extending along the railway 125 out of reach of the suspended conductor and electrically connected at intervals with the conductor or conductors with which the contact device makes connection.

10. In an electric railway, the combination 130 of two or more tracks the rails of which form return-conductors and are electrically connected together and with one pole of the generator, with a separate suspended conductor

arranged at an elevation above each of the tracks and also electrically connected together and with the other pole of the generator, one or more electrically-propelled vehicles for said railway-tracks, provided with an electric motor mechanically arranged to rotate the axle, an upwardly-extending current-collecting device making an underrunning contact with the suspended conductor, an electric circuit on the vehicle, including the motor and connecting the current-collecting device with the rails, and a supply-conductor extending along the railway out of reach of the current-collecting device and electrically connected with the conductor or conductors with which the contact device makes connection.

11. In an electric railway, the combination of a track forming a return-circuit and connecting with one pole of a generator, a suspended conductor extending along the railway electrically independent of the rails of the track and connected with the other pole of the generator, an electrically-propelled vehicle having a motor mechanically connected to rotate the axle, a current-collecting device supported wholly by the vehicle and making a traveling connection with the suspended conductor, a motor-circuit carried upon the vehicle, including the motor and connecting the collector device with the rails, and a supply-conductor extending along the railway out of reach of the current-collecting device and electrically connected with the conductor with which the contact device makes connection.

12. In an electric railway, the combination of the track-rails forming a return-circuit and connected with one pole of the generator, a suspended conductor electrically independent of the rails and having its lower surface unobstructed, an electrically-propelled vehicle provided with an electric motor mechanically connected with its axle to rotate it, an under-moving contact with the vehicle and making an electrical connection with the under surface of the suspended conductor, an electrical circuit carried by the car, including the motor and connecting the current-collecting device with the rails, and a supply-conductor extending along the railway out of reach of the current-collecting device and connected electrically with the suspended conductor with which the contact device makes connection.

13. The combination of two or more railway-tracks the rails of which are electrically connected together and with one pole of the generator, a series of poles arranged along the railway-tracks, suspended conductors for each of the railway-tracks electrically independent of the rails, but supported from said posts and electrically connected together and with the other pole of the generator, one or more electrically-propelled vehicles for said railway-tracks, provided with contact devices

for making a contact with the suspended conductors and supply current to the motors of the vehicles, and one or more supply-conductors extending along the railway-track and electrically connected with the suspended conductors at intervals.

14. The combination of two or more railway-tracks the rails of which are electrically connected together and with one pole of the generator, a series of poles arranged along the railway-tracks, suspended conductors for each of the railway-tracks electrically independent of the rails, but supported from said posts and electrically connected together and with the other pole of the generator, one or more electrically-propelled vehicles for said railway-tracks, provided with contact devices consisting of an upwardly-extending arm arranged above the roof of the vehicle and carrying a grooved contact-wheel for making an underrunning contact with the conductors and supplying current to the motor on the vehicle, and one or more supply-conductors supported upon the posts and extending along the railway-track out of reach of the current-collecting devices and electrically connected with the suspended conductors at intervals.

15. In an electric railway, the combination of a main track and turn-out railway-track the rails of which are electrically connected together and with one pole of the generator, in combination with a suspended conductor for the railway-track, and also a separate suspended conductor for the turn-out track electrically connected together and with the other pole of the generator, but electrically independent of the rails, an electrically-propelled vehicle, an upwardly-extending current-collecting device making contact with either of the suspended conductors of the two tracks, and a circuit carried upon the car, including the electric motor and connecting the current-collecting device with the rails.

16. In an electric railway, the combination of a main track and turn-out railway-track the rails of which are electrically connected together and with one pole of the generator, with a suspended conductor for the railway-track, and also a separate suspended conductor for the turn-out track electrically connected together and with the other pole of the generator, but electrically independent of the rails, an electrically-propelled vehicle, an upwardly-extending current-collecting device making contact with either of the suspended conductors of the two tracks, and consisting of an upwardly-extending arm arranged above the roof of the car and provided with a grooved contact, in the groove of which the suspended conductor rests and is guided, and a circuit carried upon the car, including the electric motor and connecting the current-collecting device with the rails.

17. In an electric railway, the combination of two tracks having their rails looped at one end and electrically connected together and

with one pole of the generator, a separate suspended conductor for each of the tracks, said conductors also being looped to correspond with the tracks and electrically connected together and with the other pole of the generator, an electrically-propelled vehicle, a contact device carried by the vehicle, making a running contact with either of the suspended conductors, and a circuit carried by the vehicle

including the electric motor and connecting the contact device with the rails.

In testimony of which invention I have hereunto set my hand.
